UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

TERMINAL-HEAD FASTENING.

Application filed July 25, 1923. Serial No. 653,691.

This invention has for its object to provide a fastening means for the terminal heads of switches and the like such as the lighting and ignition switches for automobiles.

5 With such switch constructions the terminal head of insulating material constitutes a closure for a cylindrical switch case against which spring contacts bear for making connection with contact studs carried thereby and it is the object of this invention to utilize the pressure received from the contact means for assisting the terminal head fastening means in holding the terminal head firmly in place though permitting 15 of its being easily removed.

With the above and other objects in view the invention consists in the terminal head fastening means as herein claimed and all equivalents.

20 Referring to the accompanying drawings, in which like characters of reference indicate the same parts in different views,

Fig. 1 is a rear view of an automobile switch provided with a terminal head fastening means constructed in accordance with 25 this invention;

Fig. 2 is a sectional view thereof; and

Fig. 3 is a perspective view of the terminal head.

30 In these drawings, 10 indicates a front plate having mounted on it a switch lever 11 for operating a switch member 12. On the back of the front plate is a cup-shaped switch case 13 surrounding the switch member 12 and closed at its end by a terminal head 14 of insulating material carrying contact studs 15 to be engaged by spring contacts 16 carried by the switch member 12 when the switch handle 11 is turned from one position to another. Instead of mounting the terminal head in the switch case by means 40 of screws as usual, lugs or ears 17 are formed on the edge of the switch case and project inwardly, the disk-shaped terminal head being provided with grooves 18 in its edge through which the lugs may pass when the terminal head is depressed against the action of the spring contacts 16, said lugs 17 serving to prevent the withdrawal of the 45 terminal head when it is turned so that the grooves no longer register with the lugs.

Some means is necessary for fixing the position of the terminal head with respect to the switch case, however, in order that

the proper connections may be made in the 55 various positions of the switch handle and, for this purpose, the back of the terminal head is provided with notches 19 to receive the lugs 17, the pressure of the spring contacts 16 serving to keep the parts in their 60 relative positions with the lugs engaged in the notches until the terminal head is pressed inwardly against such pressure and then turned to bring the grooves 18 into register with the lugs when it is free to be removed. 65

By means of this invention the terminal head is held rigidly in its definite position without requiring the use of screws or of spring-engaging means other than the spring contacts which co-operate with it for the 70 other purpose of effecting the electrical connections and the operation of attaching and disconnecting the terminal head is simplified.

It will be noted that the distances between the lugs 17 are not the same and that the 75 distances between the grooves and notches are correspondingly varied so that the terminal head can only fit in the switch case in the one position in which the contact studs bear the proper relation to the spring 80 contacts of the switch member so that improper assembly is impossible.

What I claim as new and desire to secure by Letters Patent is:

1. In a switch or the like, a switch case 85 having inwardly projecting lugs, and a terminal head provided with grooves in its edge through which the lugs may pass to find a seat on the ungrooved portion of the terminal head edge. 90

2. In a switch or the like, a switch case having irregularly positioned inwardly projecting lugs, and a terminal head provided with grooves in its edge positioned to correspond with the positions of the lugs and 95 adapted to have the lugs pass therethrough to take a seat on the ungrooved portion of the terminal head edge.

3. In a switch having spring acting contacts for engaging a terminal head, a switch 100 case having inwardly projecting lugs, a terminal head with notches in its edge through which the lugs may pass and seats on the terminal head engaged by the lugs.

4. In a switch or the like, a switch case 105 having inwardly projecting lugs, a spring-pressed terminal head having notches in its edge through which the lugs may pass, and

seats on the terminal head engaged by the lugs.

5. In a switch or the like, a switch case having inwardly extending lugs, and a spring pressed terminal head having grooves in its edge through which the lugs may pass and provided with notches to receive the lugs when they have passed through the grooves.

10. In a switch or the like having a spring acting contact for engaging a terminal head, a switch case having inwardly projecting lugs, a terminal head provided with grooves in its edge through which the lugs may pass and having notches to receive the lugs when they have passed through the grooves, the spring action of the switch contacts serving to hold the lugs in the notches.

7. In a switch or the like, a cylindrical sheet metal switch case having lugs bent inwardly at its edge, a switch member within the switch case having spring contacts, a disk-shaped terminal head of insulating material provided with grooves in its edge through which the lugs may pass and having notches to receive the lugs, said terminal head being engaged by the spring contacts for holding the terminal head in the position fixed by the engagement of the lugs in the notches.

8. In a switch or the like, a sheet metal

switch-case having lugs formed on its edge bent inwardly, and a fiber terminal head having its edges scored to produce grooves registering with the lugs and through which the lugs may pass to the back of the terminal head, there being indentations in the back of the terminal head to receive the lugs.

5. In a switch, a cylindrical switch-case, a disk-shaped terminal head fitting therein, and lugs on the switch-case projecting inwardly in the way of the terminal head, there being grooves in the edge of the terminal head through which the lugs pass and indentations on the back of the terminal head spaced from the grooves to receive the lugs.

10. In a switch, a cylindrical switch-case, a disk-shaped insulating terminal head fitting therein for a part of its depth, and lugs standing up on the edge of the switch-case and bent inwardly in the path of the terminal head, there being grooves in the edge of the terminal head through which the lugs may pass to the back of the terminal head and indentations in the back of the terminal head in which the lugs are seated determining the extent of projection of the terminal head from the switch-case.

In testimony whereof, I affix my signature.

EDWARD N. JACOBI.
